CLAIM

The ornamental design for a fitness monitor capsule, as shown and described.

DESCRIPTION

FIG. 1 is an isometric view of a fitness monitor capsule. FIG. 2 is side view of the fitness monitor capsule of FIG. 1. FIG. 3 is an opposite side view of the fitness monitor capsule of FIG. 1.

FIG. 4 is a top view of the fitness monitor capsule of FIG. 1.

FIG. 5 is a back view of the fitness monitor capsule of FIG. 1.

FIG. 6 is a front view of the fitness monitor capsule of FIG. 1.

FIG. 7 is a bottom view of the fitness monitor capsule of FIG. 1; and,

FIG. 8 is an off-angle view of the fitness monitor capsule of FIG. 1.

The fitness monitor capsule depicted in the accompanying figures may be part of a wearable fitness monitor that is worn on a person's wrist.

Stipple shading is used in all of the accompanying Figures to convey surface contouring and not texture.

The broken lines shown in the drawings illustrate portions of the fitness monitor capsule that form no part of the claimed

design. Surfaces that do not include stipple shading and are bounded, at least in part, by broken lines form no part of the claimed design. Thus, for example, the cover on the underside of the fitness monitor capsule, the charging port on the underside of the fitness monitor capsule, the features within the cavities of fitness monitor capsule, and the buttons of the fitness monitor capsule do not form part of the claimed design.
